(74) *Attorney, Agent, or Firm*—Shook, Hardy & Bacon, LLP.

(57) **CLAIM**

The ornamental design for a telescoping writing implement storage case, as shown and described.

DESCRIPTION

FIG. 1 is a perspective view of a telescoping writing implement storage case in an expanded state showing the new design;

FIG. 2 is a right side elevational view thereof, a left side elevational view thereof being a mirror image of the right side elevational view;

FIG. 3 is a front elevational view thereof, a rear elevational view thereof being a mirror image of the front elevational view;

FIG. 4 is a top plan view thereof;

FIG. 5 is a bottom plan view thereof; and,

FIG. 6 is a perspective view of a telescoping writing implement storage case in non-expanded state showing the new design.

The broken lines showing writing implements in FIG. 1 and the bottom in FIG. 4 are included for the purpose of illustrating environment and form no part of the claimed design.

1 Claim, 3 Drawing Sheets

FIG. 1.

FIG. 2.

FIG. 3.

FIG. 4.

FIG. 5.

FIG. 6.
